UNITED STATES PATENT OFFICE

CHARLES W. FRASER, OF TORONTO, ONTARIO, CANADA, ASSIGNOR TO THE GEORGE EVERALL COMPANY, LIMITED, OF TORONTO, CANADA

COMBINATION ENVELOPE

Application filed October 6, 1928. Serial No. 310,763.

This invention relates to double purpose envelopes and has for its object the construction of an envelope of the type described which may be cheaply and easily made and which is convenient and simple for use, which may be made from a minimum amount of material, and in which the insertion of the contents and closing the envelope is facilitated.

10 I attain my object by constructing an envelope of comparatively large size for pamphlets, catalogues or other second class mail, which envelope is left open at two adjacent sides, each of the open sides being 15 provided with a flap, one of which is gummed for sealing purposes.

To the inside of the envelope a sheet of paper is secured to form a compartment for letters or other first class mail. The open 20 side of this compartment is arranged sufficiently close to the open side of the envelope having the gummed flap, so that when the flap for that side of the envelope is sealed down, the open side of the compartment is in- 25 accessible. The other flap of the envelope is simply slipped within the envelope to prevent accidental slipping out of the pamphlet, catalogue, or other second class mail.

With this construction both classes of mail 30 may be inserted from one side of the envelope, thus avoiding the necessity of turning the envelope, while at the same time a very large opening extending over two sides of the envelope is provided. This not only greatly 35 facilitates the insertion of the second class mail but makes the opening of the first class mail compartment more easily got at.

The invention is hereinafter more fully described and is illustrated in the accompany- 40 ing drawings in which

Fig. 1 is a plan view of the envelope showing the flaps open;

Fig. 2 is a section through the envelope on the line 2—2 in Fig. 1, looking from right to left, showing the envelope in its closed condition;

Fig. 3 is a plan view of the blank from which the envelope is made;

Fig. 4 is a longitudinal section partly 50 broken away of an alternative form of the en-

velope; and

Fig. 5 is an end view of the said modified form.

In the drawings like numerals of reference indicate corresponding parts in the different 55 figures.

1 represents the front or address side of the envelope and 2 the back of the envelope, which is hinged at its lower edge to the front of the envelope. A flap 3 is secured to one 60 end of the front of the envelope and sealed over the free edge of the back of the envelope. A flap 4 is provided at the top edge of the back of the envelope and adhesive matter 8 is provided on its free edge whereby it is adapt- 65 ed to be sealed over the upper edge of the front 1 of the envelope.

A flap 5 is attached to the front 1 of the envelope at the other end thereof. This flap is adapted to be turned into the opening be- 70 tween the front and back or may be turned over and detachably secured in some known manner to the back of the envelope.

A partition 6 is glued to the front of the envelope on the inside thereof, preferably ad- 75 jacent the upper left hand side of the envelope. This partition is secured along three of its edges, but its top is open and adjacent the upper edge of the envelope and is adapt- ed to be closed and sealed when the flap 4 is 80 turned over and sealed.

The compartment above referred to is adapted to carry a letter or other first class mail. An opening or transparent portion 7 may be formed in the front 1 of the envelope 85 in such a position as to make a name or address written on an inserted letter visible and readable through the front 1 from the out- side.

Suitable directions for the use of the en- 90 velope may be printed thereon and a space marked for affixing first class postage for the first class matter and another space for postage for the other matter of other classes.

While one specific method of forming the 95 envelope is described, it may be seen that the construction of the envelope may be varied considerably without departing from the gist of my invention, which consists of an envelope permanently sealed at two adjacent 100

sides, and open at the other adjacent sides for the insertion of mail matter of different classes, one of the sides being adapted to be sealed to close permanently the one side of the envelope and the first class mail compartment, and the other side being adapted to be closed in such a manner that the second or lower class contents of the envelope are accessible for inspection by the postal authorities.

Figs. 4 and 5 show an alternative form of my improved envelope. In this construction the partition 6 is left open adjacent the left hand end of the envelope, and is adapted to be closed by the flap 5, so that the letter compartment is accessible as well as the main interior of the envelope. This construction is useful where the letter compartment is used to hold circulars etc. which may be mailed at reduced rates if not sealed.

What I claim is:

In an envelope, a front and back portion hinged at one side, and having a flap formed on one portion, adjacent the hinged side, said flap being sealed over the other portion, closing one side, and leaving two open adjacent sides through which mail matter may be readily inserted; a flap on one portion provided with adhesive matter on its free edge whereby it is adapted to be sealed over the free edge of the other portion, sealing another side; a partition secured along its edges to the inside of one of said portions and having one free edge near the side of the envelope which is adapted to be sealed by the last mentioned flap, thus forming two coterminous openings adapted to be sealed by the one flap; and a flap on one portion adapted to close a side of the envelope adjacent the last mentioned side, said flap being adapted to be releasably held in its side closing position.

Signed at Toronto, Canada, this 28th day of August, 1928.

CHARLES W. FRASER.
